His Attorney

UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

ELECTRIC SWITCH.

Application filed October 31, 1918. Serial No. 280,455.

To all whom it may concern:

Be it known that I, EDWARD M. HEWLETT, a citizen of the United States, residing at Schenectady, in the county of Schenectady, 5 State of New York, have invented certain new and useful Improvements in Electric Switches, of which the following is a specification.

My invention relates to electric switches and has for its object to provide an improved electric switch of the oil break type.

The novel features which I believe to be characteristic of my invention, will be definitely indicated in the claims appended hereto, while the features of construction and mode of operation will be understood by reference to the following description taken in connection with the accompanying drawing which shows the preferred embodiment of my invention and in which:

Fig. 1 is a front elevation, partly in section, of a switch embodying my invention and Fig. 2 is a top elevation of the switch shown in Fig. 1.

The switch embodying my invention, as shown in Fig. 1, comprises a metallic vessel 1, preferably of steel, and adapted to contain oil or other insulating fluid. Mounted within the vessel 1 are relatively movable coöoperating contacts, separable beneath the surface of the fluid. Extending into the vessel 1, beneath the surface of the oil, are insulator terminal members 2 and 3 for the switch, supporting at their lower ends the fixed contacts 4. Coöoperating with the fixed contacts 4 is the movable or bridging contact 5, carried at the end of an insulated operating rod 6, which is operative with a reciprocating motion by any suitable operating mechanism, not shown, to carry the movable contact 5 into and out of engagement with the fixed contacts 4 to control the circuit through the switch.

The vessel 1 is provided with a cover member 7 to which the terminal members 2 and 3 are secured and from which the vessel is removably supported, as will be described. This cover member 7 is preferably a casting, provided with a downwardly projected portion or member 8 preferably integral therewith. Secured to the bottom of the member or wall 8, is a metal plate or member 9, preferably of steel,

through which the terminal members 2 and 3 pass with slight clearance. The member 8 coincides in configuration with the top of vessel 1 and is arranged to fit into the top of the vessel to substantially close the vessel except for the small openings in plate 9 around the terminal members 2 and 3. The member 9 also cooperates with member 8 to provide an air chamber within the cover member. The cover member 7 is also provided with portions 10 which overhang or extend over the vessel 1 and slightly down the sides thereof. These overhanging portions are open at their lower ends to communicate with the air and are provided with chambers or pockets which communicate with the inner chamber 70 of the cover 7 through openings 11 provided in the partition member 8. The openings 11 are provided with baffling means comprising a plurality of plates 11^a having staggered openings therein to permit gases to escape therethrough but to prevent the escape of insulating fluid.

The vessel 1 is removably mounted or suspended from the cover member 7 by means of tie rods 12 passing through the cover, preferably through the overhanging portions 10 and which are removably secured at their lower ends to a cradle or supporting member 13 at the bottom of the vessel 1 and within which the vessel is carried. The supporting member 13 carries ears or extensions 15, as best shown in Fig. 2, between which the rods 12 extend. The lower ends of the rods also extend through members 14 which are detachably secured to the cradle 13 but which serve to lock or hold the rods 12 in engagement with the cradle. For detachably securing the members 14 to the cradle, I preferably make the members substantially L-shaped in configuration and provide in the cradle openings into which one end of the L-shaped members is inserted. Suitable locking nuts at the ends of the rods are then tightened to rigidly lock and hold the cradle 13, vessel 1 and cover 7 together. To remove the vessel 1 the nuts at the ends of the rods 12 are loosened whereby the locking members 14, together with the ends of rods 12, are movable free from the cradle 13. The cradle can then be removed and the tank

lowered or the cover removed therefrom by any well known means.

It is well known that in the operation of switches of the above character, that the separation of the contacts 4 and 5 under load, splashes oil and causes the evolution of a large volume of hot gases which, when mixed with air, form explosive gaseous mixtures. These explosive mixtures are often ignited on further evolution of hot gases by the subsequent operation of the switch, causing explosions which frequently wreck the switch. By the novel construction of my invention, I overcome these disadvantages by providing a practically closed vessel 1 of steel construction. The steel plate 9 substantially closes the vessel 1 causing the gases evolved, as the switch operates, to fill the small air space in the vessel above the oil, in which space not enough air is mixed with the gases under usual conditions, to form explosive mixtures. Should explosions occur within the vessel under unusual conditions, the vessel 1 is of a construction to withstand the shock of such explosion without injury. These gases pass through the small openings in plate 9 surrounding the terminal members 2 and 3 and into the chamber provided by the cover member 7 and from this chamber pass out through the openings 11 and baffles 11^a into the pockets of the overhanging portions 10 and are then deflected downwardly away from the live parts of the switch into the air. The plate 9 furthermore prevents an excessive splashing of oil into the chamber of the cover member 7 and the member 8 and baffles 11^a further prevent the escape of any oil ejected into the chamber of the cover member. Should explosive mixtures occur within the chamber of the cover member 7 and become ignited such explosions merely damage the cover member and the switch itself is unharmed. Should, under unusual conditions, explosions occur within the vessel 1, the rugged cover 7 and the cradle 13 held together by tie rods 12 serve to enable the vessel 1 to effectively resist the excessive strains and stresses due to such explosions. For switches of high current carrying capacity, the cover 7 and plate 9 are preferably made of non-magnetic metal.

What I claim as new and desire to secure by Letters Patent of the United States, is:—

1. An electric switch comprising a vessel adapted to contain an insulating fluid, relatively movable contacts separable within the fluid in said vessel, a cover formed with passages for the escape of gases formed at the opening of the switch, and a plate secured directly to said cover and arranged to protect the cover from the shock occurring at the separation of the contacts.

2. In a switch, a vessel adapted to contain insulating fluid, contacts separable within said fluid, a cover for said vessel formed of a casting having a depending wall, a plate adapted to protect said cover from the shock occurring at the opening of the switch, said plate being secured to said depending wall near its lower edge, and means securing said cover to said vessel, said means being attached to the cover at a point near the upper portion of said depending wall.

3. The combination with a cover member having a downwardly extending member provided with openings, a metal plate secured to the bottom of said downwardly extending member to form a chamber within said cover, said cover having portions so thereof enclosing said downwardly projecting member and provided with pockets communicating with said openings into said chamber and open below to the air, and a vessel adapted to contain oil removably suspended from said cover member and substantially closed by said plate.

4. An electric switch comprising a vessel adapted to contain an insulating fluid, relatively movable cooperating contacts separable in said fluid, a cover member for said vessel, and means for supporting said vessel from said cover comprising a cradle for the bottom of said vessel, tie rods having clamping means thereon for connecting said cradle to said cover, said cradle having laterally opening slots for receiving said tie rods, and removable means engaging said cradle and the tie rods to prevent lateral movement of said tie rods.

In witness whereof, I have hereunto set my hand this 29th day of October 1918.

EDWARD M. HEWLETT.
